UNITED STATES PATENT OFFICE.

WILLIAM HENRY ALEXANDER, OF LONG BRANCH, NEW JERSEY.

CONCRETE-MOLD.

1,047,605.

Specification of Letters Patent. Patented Dec. 17, 1912.

Application filed April 7, 1911. Serial No. 619,552.

To all whom it may concern:

Be it known that I, WILLIAM H. ALEXANDER, a citizen of the United States, and a resident of Long Branch, in the county of 5 Monmouth and State of New Jersey, have invented a new and Improved Concrete-Mold, of which the following is a full, clear, and exact description.

My invention relates to concrete molds 10 and it has for its object to provide one having a bottom member which may be conveniently rotated and lowered so that a detachable end member will rest on the ground, the mold being provided with side members 15 which have clamps for engaging the detachable end member, and means by which the side members are moved laterally relatively to the bottom member.

Additional objects of the invention will 20 appear in the following complete specification, in which the preferred form of the invention is disclosed.

In the drawings similar characters of reference indicate corresponding parts in all 25 the views, in which—

Figure 1 is a side elevation of the invention; Fig. 2 is a fragmentary sectional view on the line 2—2 of Fig. 1, with the body member disposed in a vertical position; Fig. 30 3 is a front elevation of Fig. 2; Fig. 4 is an end view showing the body member in an inverted position; Fig. 5 is a sectional elevation showing the body member in a vertical position; Fig. 6 is a fragmentary sectional 35 view showing the means by which the clamping members are connected with the rods, by which they are operated; and Fig. 7 is a perspective view showing one of the bearing members.

40 By referring to the drawings it will be seen that a frame is provided, consisting of the side members 5, which are connected by a transverse member 6, which is right angular in cross section, this transverse member 6 being riveted to the side members 5 at 7. Supporting wheels 8 are journaled in the sides 5 of the frame. The top of the side members 5 have bearing surfaces 9, on which the bearings 10 of the bearing members 11 are adapted to rest, these bearing members 11 having guide members 12, which are disposed in the guideways 13, secured to the side members 5. At the lower terminals of 45 the guide members 12 there are depending ears 14, which are adapted to be engaged by

the cams 15, which are pivoted at 16 to the side members 5.

Secured to a rock shaft 17, which is journaled in bearings 18 in the side members 5, there are cams 19, these cams 19 being adapted to engage the cams 15 for moving them, and raising the guide members 12. Stops 20 are secured to the side members 5 for limiting the movement of the cams 19. There is secured to the shaft 17, at the outer 65 side of one of the side members 5, a lever 21, by which the rock shaft 17 may be conveniently moved, as may be desired.

Journalized in the bearings 10 there is a body member 22 having flanges 23, which 70 are engaged by the flanges 24 on the end member 25 which forms a part of the body member, the flanges 23 and 24 being secured together by bolts 26. A stud 27 is disposed in an opening 28 in the body member 22, this stud 27 being held in place by a set screw 29. Mounted to rotate on the stud 27 there is a wheel 30 having cam grooves 31. Fulcrumed at 32 to the bottom of the body member 22 there are levers 33, one set of 80 terminals 34 of the said levers 33 being disposed in the cam grooves 31, the other set of terminals 35 of the levers 33 being articulated to laterally disposed tie members 36, these tie members 36 having upwardly disposed terminals 37. Two side members 38 are provided, these side members resting normally on the body member 22, the body member 22 having lateral projections 39, which are adapted to support the side members 38 when they are moved outwardly. Straps 40 are secured to the outer sides of the side members 38, and in these straps 40 there are disposed tie members 41, the tie members 41 having straps 42 in which are 95 disposed the terminals 37 of the tie members 36.

Blocks 43 are secured to the sides of the side members 38, so that when the tie members 36 are drawn inwardly, they will carry 100 with them the side members without any lost motion. The clamping members 41 have flanges 44, which are normally disposed in recesses 45, in the removable end member 46 of the mold. Springs 47 are provided one 105 for each of the clamping members 41, the springs connecting the clamping members with one set of straps 40, so that the clamping members 41 will be held yieldingly in a predetermined position relatively to the side 110

members 38, the end member 25 of the mold having lateral projections 48, each with a slot 49, the clamping members 41 being disposed in these slots 49. The head members 50 are provided with threaded orifices in which the terminals 51 of the clamping members 41 are disposed, nuts 52 being provided for engaging the threaded terminals 51 to lock the head members 50 in position.

10 Articulated to the head members 50 one at each side, there are links 53, these links 53 being connected by a transverse member 54 to abut against the terminals 51 of the clamping members for moving the said terminals inwardly. The link members 53 have terminals 55, which rest against the rear of the lateral projections 48 of the end member 25. To the terminals 55 of the links 53 there are articulated brackets 56, the brackets 56 at each side of the machine being riveted to rods 57, the rods 57 being articulated to wrist pins 58, secured to the wheel 30. The wheel 30 is provided with a crank 59, by which it may be conveniently turned.

15 Projecting from one of the bearings 10 there is a journal 60, to which a head member 61 is articulated on an axis which is vertical when the body member is in horizontal or normal position. Secured to this head member 61 there is an arm 62, with a hook 63, the hook 63 being adapted to engage and rest in the recess 64, in the bracket 65, which is integral with one of the side members 5. A lever 66 is secured to the head member 61, 20 the axis of the lever being at right angles to the axis of the pivot 67, which connects the head member 61 with the journal 60. A transverse member 6 is provided with a threaded head 68, in which meshes a screw 69, the screw 69 being provided to engage the body member 22 at 70, and serve as a stop for the body member.

25 In using the invention the side members 38 and the removable end member 46 are disposed in position with the flanges 44 engaging the recesses 45 in the removable end member, and with the clamping members 41 drawn rearwardly and toward the center line of the machine to lock the side members and removable end members, the mold formed by the body member the side members and the end members, is filled with concrete. The device is then moved into a position where the operator desires to 30 move the concrete which is disposed in the mold. The operator moves the lever 66 toward the center line of the machine, which disengages the hook 63 from the recess 64, in the bracket, and he then raises the lever 66 to rotate the mold to the position shown in Fig. 5 of the drawings. The lever 21 is then raised slowly, the movement of the cams 19 permitting the cams 15 to move downwardly and with them the bearing members 12. In this way the mold is moved

toward the ground until the removable end member 46 rests on the ground. The operator then rotates the wheel 30 by means of the crank 59, so that the rods 57 are moved outwardly, and the arms 34 of the levers 33 are moved inwardly. This movement of the wheel 30 will move the links 53 into the position shown in Fig. 2 of the drawings which will draw the clamping members 41 outwardly, and with them the rear of the side members 38, and also free their flanges 44 from the recesses 45. At the same time the movement of the levers 33 will move the tie members 36 outwardly. As the clamping members 41 and the tie members 36 are moved outwardly they will carry with them the side members 38, and will permit the operator to raise the mold by a downward movement of the lever 21, the concrete being deposited on the removable end member 46, and being disengaged from the body member 22 of the mold, when it is raised. As the side members 38 have been moved away from the concrete by the rotation of the wheel 30, only one surface of the mold is in contact with the concrete when the body member is raised. However, if desired, the device may be moved rearwardly from the concrete so that the concrete will no longer be in contact with any member of the mold, when the body member is raised by the downward movement of the member 21. After the body member has been raised as has been described the lever 66 is operated to bring the body member to a horizontal position, as it is moved outwardly, so that the hooks 63 will be again disposed in the bracket 65. Another end member 46 is then provided, and is disposed in position, when by a rotary movement of the crank 59 the flanges 46 on the clamping members 41 will be locked in the recesses 45, in the new end member 46, and, at the same time, the side members 38 will be drawn inwardly, and will be locked with the end member 36, to permit of the re-filling of the mold. It will be understood that when the clamping members 41 are moved to lock their flanges 44 in the recesses 45 in the new end member 46, the springs 47 will draw the side members 38 into place.

Having thus described my invention, I claim as new and desire to secure by Letters Patent:

1. In a concrete mold a frame having a vertical guideway, a bearing member for traveling in the guideway, a body member journaled in the bearing member, means for supporting the bearing member in adjusted position in the guideway, a side member movable laterally relatively to the body member, a removable end member, a clamping member normally engaging the end member for holding the end member in position relatively to the body member when the

body member is disposed horizontally, the clamping member being adapted to be disengaged from the end member to permit the end member to remain on the ground free from the body member, when the body member is disposed vertically, and has been lowered by the downward movement of the bearing member in the guideway, and a member for moving the side member laterally relatively to the body member.

2. In a concrete mold a frame, having a vertical guideway, a bearing member for traveling in the guideway, a body member journaled in the bearing member, means for supporting the bearing member in adjusted position in the guideway, a side member movable laterally relatively to the body member, a removable end member, a clamping member normally engaging the end member, for holding the end member in position relatively to the body member when the body member is disposed horizontally, the clamping member being adapted to be disengaged from the end member to permit the end member to remain on the ground free from the body member, when the body member is disposed vertically, and has been lowered by the downward movement of the bearing member in the guideway, a member for moving the side member laterally relatively to the body member, and means for operating the last-mentioned member and the clamping member simultaneously.

3. In a concrete mold a body member having a front end and a laterally extending member at the rear of the front end, a side member movable laterally relatively to the body member, a removable end member normally disposed at the front end of the body member, a clamping member engaging the removable end member and extending rearwardly beyond the second member, means by which the clamping member is adapted for moving the side member, a link pivoted at one end to the rear of the clamping member and engaging the second member at the other end, and means for moving the last-mentioned end of the link relatively to the body member.

4. In a concrete mold a body member, a side member movable laterally relatively to the body member, a removable end member at one end of the body member, a clamping member engaging the end member and having a terminal extending rearwardly beyond the other end of the body member, a link pivoted to the said terminal of the clamping member, the link engaging the body member, means for moving the link relatively to the body member for moving the clamping member longitudinally and laterally relatively to the body member, and a tie member having means for moving the side member.

5. In a concrete mold a body member, a

side member movable laterally relatively to the body member, a removable end member at one end of the body member, a clamping member engaging the end member having a terminal extending rearwardly beyond the other end of the body member, straps secured to the side member through which the clamping member is disposed, a link pivoted to the terminal of the clamping member, the link engaging the body member, means for moving the link relatively to the body member, for moving the clamping member longitudinally and laterally relatively to the body member, and a tie member having means for moving the side member.

6. In a concrete mold a body member, a side member movable laterally relatively to the body member, a removable end member at one end of the body member, a clamping member engaging the end member and having a terminal extending rearwardly beyond the other end of the body member, a link pivoted to the said terminal of the clamping member, the link engaging the body member, means for moving the link relatively to the body member for moving the clamping member longitudinally and laterally relatively to the body member, a tie member disposed under the body member and having means for moving the side member, and means for moving the link and the tie member simultaneously.

7. In a concrete mold a body member having a slot, a side member having a strap and movable laterally relatively to the body member, a removable end member at one end of the body member, a clamping member engaging the removable end member and disposed in the strap, and in the slot, and having a terminal extending beyond the other end of the body member, a link pivoted to the clamping member and engaging the last-mentioned end of the body member, and means for moving the link relatively to the body member for moving the clamping member longitudinally and laterally relatively to the body member.

8. In a concrete mold a body member having a slot, a side member having a strap and movable laterally relatively to the body member, a removable end member normally disposed at one end of the body member, a clamping member engaging the removable end member, and disposed in the strap and in the slot, and having a terminal extending beyond the other end of the body member, a link pivoted to the said terminal of the clamping member, the link engaging the body member, means for moving the link relatively to the body member for moving the clamping member longitudinally and laterally relatively to the body member, and a tie member having means for engaging the side member for moving the latter.

9. In a concrete mold a body member, two

side members movable laterally relatively to the body member, two tie members, means by which the tie members are adapted for moving the side members, a wheel journaled 5 to the body member, and having an eccentric groove and two levers fulcrumed to the bottom of the body member, one set of terminals of the levers being disposed for traveling in the eccentric groove, the other set 10 of terminals being pivoted to the tie members.

10. In a concrete mold a body member, a side member movable relatively to the body member, a removable end member, a clamping 15 member having a flange for engaging the end member to hold the end member in normal position, a tie member, means by which the tie member is adapted for moving the side member, a wheel journaled to 20 the body member, and means by which the wheel is adapted to operate the tie and clamping members.

11. In a concrete mold a body member, a side member, movable laterally relatively to 25 the body member, a removable end member, a clamping member for holding the end member in a normal position, a tie member, means by which the tie member is adapted for moving the side member, a wheel journaled 30 to the body member and having a cam groove, means by which the wheel is adapted to operate the clamping member, a lever fulcrumed to the body member, one arm of the lever being disposed in the cam groove, 35 and means by which the other arm of the lever is adapted for operating the tie member.

12. In a concrete mold a body member, a side member movable relatively to the 40 body member, and a removable end member normally disposed at one end of the body member, a clamping member for holding the removable end member in normal position, the clamping member having 45 a terminal extending away from the said end of the body member, a tie member, means by which the tie member is adapted for moving the side member, a wheel journaled to the body member, means by which 50 the wheel is adapted to operate the tie member, a link pivoted to the said terminal of the clamping member, the link extending in the direction of the said end of the body member and engaging the body member, the 55 link being adapted to move the clamping member longitudinally and laterally relatively to the body member, and a rod connected with the link and articulated to a wrist pin on the wheel.

60 13. In a concrete mold a body member, two side members movable relatively to the body member, a removable end member normally disposed at one end of the body member, two clamping members for holding the 65 removable end member in normal position,

the clamping members having terminals extending away from the said end of the body member, links pivoted at one set of ends to the said terminals of the clamping members, the links extending in the direction of 70 the said end of the body member, and engaging the body member, the links being adapted to move the clamping members longitudinally and laterally relatively to the body member, a wheel having cam 75 grooves, rods articulated to the wheel and to the links, a tie member having means for moving the side members, levers fulcrumed to the body member, one set of arms of the levers being disposed in the cam 80 grooves, and the other set of arms of the levers being pivoted to the tie members.

14. In a concrete mold a body member, two side members having straps and movable relatively to the body member, a removable end member normally disposed at one end of the body member, two clamping members disposed in the straps and engaging the removable end member, the clamping members having terminals extending 85 away from the said end of the body member, links pivoted to the said terminals of the clamping members, the links extending in the direction of the said ends of the body member, and engaging the body member, 90 means on the links for engaging the sides of the clamping member, respectively, the links being adapted for moving the clamping members longitudinally and laterally relatively to the body member, a wheel having 95 cam grooves, rods pivoted to the wheel and to the links, tie members having means for moving the side members, and levers fulcrumed to the body members one set of arms of the levers being disposed in the 100 cam grooves the other set of arms being pivoted to the tie members.

15. In a concrete mold a body member, a side member movable relatively to the body member, a removable end member, a clamping member engaging the end member, means by which the clamping member is adapted for moving the side member, the clamping member having a terminal extending in the direction of the other end of the 110 body member, two links pivoted at opposite sides of the clamping member, the links extending in the direction of the first-mentioned end of the body member and engaging the body member, a transverse member 115 connecting the links and engaging the side of the clamping member, so that the links with the transverse member are adapted to move the clamping member longitudinally and laterally relatively to the body member, 120 and a rod secured to the links by which they are adapted to be operated.

16. In a concrete mold a body member, a removable end member normally disposed at one end of the body member, a clamping 130

member engaging the end member, the clamping member having a terminal extending in the direction of another end of the body member, a link pivoted to the said 5 terminal of the clamping member, the link extending in the direction of the first-mentioned end of the body member, and engaging the body member, means on the link for engaging the side of the clamping member 10 so that when the link is moved relatively to the body member it will move the clamping member longitudinally and laterally relatively to the body member, and means for moving the link relatively to the body member. 15

17. In a concrete mold, a body member having an end, a removable member normally disposed at the said end of the body member, a clamping member engaging the 20 removable end member, the clamping member having a terminal extending away from the said end of the body member, a link pivoted to the terminal of the clamping member, the link extending in the direction 25 of the said end of the body member and engaging the body member, and means for moving the link relatively to the body member.

18. In a concrete mold a frame having a 30 vertical guideway, a bearing member disposed for moving in the guideway, a body member journaled in the bearing member, a detachable end member for the body member, a member pivoted to the frame on which the bearing member rests, means for supporting and operating the pivoted member 35 so that when the body member has been rotated to a vertical position with the detachable end member downward, the body member 40 may be lowered to the ground by operating the pivoted member for lowering the bearing member in the vertical guideway and the detachable end member resting on the ground may be freed from the body member. 45

19. In a concrete mold a frame, a bearing supported on the frame, a body member journaled in the bearing, a lever fulcrumed to the body member on an axis at an angle 50 to the axis of the bearing, and a hook on the lever for engaging the frame for supporting the body member, the lever being adapted for moving the hook away from the member of the frame and for rotating the body member. 55

20. In a concrete mold a frame having a vertical guideway, a bearing member disposed for moving in the guideway, a body member journaled in the bearing member, a detachable end member for the body member, adjustable means for supporting the bearing member in the guideway so that when the body member has been rotated to a vertical position, with the detachable end member next the ground, the body member, 60

with the detachable end member may be lowered to the ground by operating the said means to lower the bearing member in the guideway and the detachable end member may be freed from the body member. 70

21. In a concrete mold a frame having a vertical guideway, a bearing member disposed for moving in the guideway, means mounted on the frame for supporting the bearing member in a predetermined position relatively to the frame, a body member journaled in the bearing, a lever fulcrumed to the body member on an axis at an angle to the axis of the bearing member, and a hook on the lever for engaging a member of the frame for supporting the body member, the lever being adapted for moving the hook away from the member of the frame, and for rotating the body member. 80

22. In a concrete mold a frame having a vertical guideway, a bearing member disposed for moving in the guideway, means mounted on the frame for supporting the bearing member, in a predetermined position relatively to the frame, a body member, 85 journaled in the bearing, a side member movable relatively to the body member, a detachable end member, and a clamping member engaging the end member for holding the end member in place and secured to 90 for moving the side member. 95

23. In a concrete mold a frame, a bearing supported on the frame, a body member journaled in the bearing, a lever fulcrumed to the body member on an axis at an angle 100 to the axis of the bearing, a hook on the lever, for engaging a member of the frame for supporting the body member, the lever being adapted for moving the hook away from the member of the frame, and for rotating the body member, a side member movable relatively to the body member, a removable end member, a clamping member for engaging the end member for holding the end member in position relatively to the 105 body member, and a member for moving the side member relatively to the body member. 110

24. In a concrete mold a frame having a vertical guideway, a bearing member disposed for moving in the guideway, means mounted on the frame for supporting the bearing member in a predetermined position relatively to the frame, a body member journaled in the bearing, removable side 115 members for the body which are disposed thereon, one at each side, a removable end member which is disposed at one set of ends of the side members, and means for clamping the removable end member in position. 120 125

25. In a concrete mold a body member, two side members, one disposed at each side of the body member, a removable end member, clamping members for the end member, and springs connecting the side mem- 130

bers with the clamping members for assisting in moving the side members into position when the clamping members are moved to hold the end member in position.

5 26. In a concrete mold a body member, an end member, clamping members engaging the end member, side members, straps on the side members through which the clamping members are disposed, and means 10 for moving the clamping members longitudinally and laterally.

27. In a concrete mold a body member, an end member, clamping members engaging the end member, and movable longitudinally and laterally, side members, loops on 15 the side members through which the clamping members are disposed, springs connecting the side members with the clamping members, and means for moving the clamp-

20 ing members longitudinally and laterally, for operating the side members and for engaging and disengaging the end member.

28. In a concrete mold a frame having a vertical guideway, a bearing member for

traveling in the guideway, a body member 25 journaled in the bearing member, means for supporting the bearing member in adjusted position in the guideway, a removable end member, and a clamping member normally engaging the end member for holding the 30 end member in position relatively to the body member when the body member is disposed horizontally, the clamping member being adapted to be disengaged from the end member, to permit the end member to remain on the ground free from the body member, when the body member is disposed vertically, and has been lowered by the 35 downward movement of the bearing member in the guideway.

40 In testimony whereof I have signed my name to this specification in the presence of two subscribing witnesses.

WILLIAM HENRY ALEXANDER.
